(54) **PRINTING, ART OF**

(76) Inventor: **William M. Dodge**

William M. Dodge
S. Cutters Patent

The selection referred to in these Sitter's intent and making part of the same containing a description in the words of the late William the Dodge himself of his improvements in the art of printing. —

his improvement consists in the construction and use of types and apparatus for printing.

These pieces are in some respects similar to those in common use; but the mode of supporting the pressure is by means of rollers resting in sockets on inclined planes as substitutes for the tenons. The rollers are cylindrical elliptic or conical according as the construction of the construction of the press requires but the sections may be either circular sections or either of the two figures following. The curve of the two opposite sides of said figures or have the two opposite sides upon such which the pressure is exerted either cylindrical conic or spherical and fitted into sockets or cavities of a corresponding shape; and while one of these cavities is stationary the other or others of them must be movable so that it will be lateral. Motion is given it changes the pressure in a distance between the two curves that is when applied to the press may press it allows the movable cavity to rise or fall by the motion of the bar. Thus suppose a cylindrical cavity to be made in the top of the platter, and another to be made directly on it in the middle side of the head of the press and two of the above named sections fitted into these cavities while the opposite sides of the sections come in contact when the platter is pressed sufficiently hard upon the type or forme. The platters are drawn nearly by a perpendicular direction upon their sides while the same are in contact it is made by means of a cylindrical cavity in the lower one and a semicircular projection on the upper one. After this part the bar is connected by a link so that when it is pulled forward the platter is forced down upon the type the bar

being secured to a perpendicular spindle which vibrates on strings secured to one of the cheeks or sides of the press, and the link being connected to the bar by a joint at near the centre of motion, so that its turns which the sections require to move will admit.

The sections of a cone produce the same effect as those of a cylinder when the proportions are similar but are somewhat more difficult of application. Thus suppose the common bar and spindle to be used without the threads of the screw. Take two pairs of pins from eight to twenty-four inches long and hold a globular piece of lead in each end of these bars, which is in what may be termed the sections. Make globular cavities in the opposite sides of the bar and the similar ones in the head of the press, so that these bars will fit into both cavities at once and extend from the head of the press to the bar by moving the bar to and fro in the usual way, the platter will rise and fall. The sections should be so situated that when the bar is pulled forward and the press is forced, they should stand on opposite sides of the spindle at equal distances from it and nearly perpendicular. The upper cavities may in all instances be made in the top of the sections instead of the head of the press. The weight of the platter acting as may be suspended till the spring or other things

in the complete cylinder come in contact with the sections, retaining the course of either of these figures. In a similar plane a wedge is introduced above and below the rollers or between them, so as to graduate the pressure to any required force; this the simplest form is to hold the steel on the rollers in such a manner as to form inclined planes on their surfaces which come in contact so that these planes may be formed on the platter, or on the head of the press. Otherwise, separate wedges may be introduced above or below the rollers, for the purpose of increasing or diminishing the pressure at pleasure.

The bar or iron may be used to move the rollers, as before described, or any other mode of attaching the moving parts of the rollers to any joint in the bar which will give them the necessary motion.

will answer the purpose. But the most effectual mode of avoiding friction is to let a propeller pin extend upward from the common bar, & the propeller pin to give the required motion, make a square hole in the link which connects the bar with the rollers which will should be so large as to prevent the pin from coming in contact with any part of it except that side against which the propeller is exerted. By this means the pin, rolls upon the surface against which the propeller is exerted, instead of slipping in the usual way. The link may be connected with pins extending from each end of the roller in the same way as to avoid the friction, at both ends shall easily. Where there is a reciprocating propeller and motion the part which comes in contact should be made of the best of steel and hardened and, more upon sections of circles and, instances in the way described.

Another application in which the rollers may be used, to produce the impression is to adapt the type to a cylinder by using spaces between the lines in the form of a wedge. These spaces should be so cast as to fit into the niches in the type to prevent them from falling out of their places as the roller revolves. The spaces may likewise extend into the furniture of the form or into the chase to hold the type the more secure, or the type may be cast in form of a wedge, it may be set around the roller without resorting to spaces to form. The circles, small rings, may be introduced into the niches of the type and extend into the circular chase and furniture to secure them instead of spaces. The type being set round the similar rollers of suitable size, certain one or more being, each the other rollers are caused to revolve in contact with the face of the type. Blanketed and type face directly of the usual kind are formed on these last mentioned two rolling which with those containing the type are so arranged that the paper to be printed passes between them. And let a sheet of paper be tightened horizontally, at one end place one of the type rollers under it and at the other end place the other type roller over the sheet. Under the latter and over the former

are placed the separate rollers on which are wound, the blankets to be. These are all so connected together by cog wheels that they revolve in exact concert, so that the register is made more perfect than when it is in the usual way. One of the cog wheels is connected with its type roller by, so as to that its position can be changed at pleasure, in making registers. A continuous line may be passed between these rollers, and printed with great dispatch on both sides by, first winding it upon a roller, while passing it under these rollers, passing it between those above deposited, and after bearing these it may be either wound up on another roller or passed off to dry in the same manner, as it is dried in the paper-staining business. Each of the type rollers is supplied with ink by three or more rollers having to roll on clothes, wound round them and covered with the same, leather or skins with which the common impressions rollers are covered; these revolve in contact with the face of the rollers and are supplied by another roller which passes to and fro round the outside of the roller touching each as it moves. This may be supplied by other distributing rollers (revolving on their axles) by the motion of either of either of those first mentioned, to which the ink is applied by a common tray or by a cylindrical brush revolving in a vessel containing ink. The ink may be equalized on the distributing rollers by a small roller moved by machinery or by hand backward and forward across them or it may be equalized in this manner on a board, and then applied to the rollers.

The other apparatus belonging to the subscriber, improved and in the art of printing is described as follows: The box and platter of the press are to be each of the size of the forms to be printed. The box is placed horizontally slightly inclined, so as similarly and the platter is brought to it in the same manner and to cover the surface, impress a the common type face; and when it is brought down on the form the impression is produced by an application of the press, done before, revolved upon the end of the platter opposite to the hinge. The platter is then raised and the sheet removed the usual way.

or there may be the frisket of the common kind, being in the well-known typeman, without covering by a hinge or sticks or leading from the middle of one of the friskets, which are hinged together at one end and pasted or covered in the usual way. The sheet being between the friskets can be placed on the form first one side down and then the other by turning them upon the sticks. The friskets are held together by a slight catch and the sheet can be easily placed by prints and corresponding holes in the friskets. In this case the blanket and typeman sheet are attached to the platter in either the ways as before mentioned or is suspended in the usual way. And in case of printing both sides of the paper as above before it is removed from the friskets, the typeman sheet should be longer than normal and receive it more laterally upon the face of the platter as to prevent the ink which adheres to it from striking the paper while printing and a cylinder brush or roller may be used to remove or abrade the ink as the typeman sheet passes to and fro in contact with it. For the purpose of changing the typeman sheet a little one method is to have his rolling one at each end of the platter on which the typeman sheet (which may be ^{thin} paper or other cloth or paper) may be alternately removed by the motion of the prints.

The ink may be applied by rollers as follows. Prepare two or more rollers as before described and range them in a frame, to which connect them with a rod of suitable length and drive to move the rollers forward and back across the form. The rod may be moved by a spur cog wheel which is a shaft in the rear of the prints which will mesh into a rack or cog on the rod. This wheel may be put in motion by a bevel cog wheel, in the same way, which may be worked by another bevel wheel connected to the back hinge of the platter. There may be a cogging of wheels of suitable size to produce the required motion, or any other plan may be adopted to produce a lateral motion in the rollers by the motion of the prints. The distributing rollers placed at the back of the form may

may be turned by a bevel dog wheel on one of their axles, meshing with a larger wheel also on the back hinge of the platter. These rollers bring in contact with each other and ensure an equal distribution of ink. The ink may be supplied to these rollers as before, viz., by a cylindrical brush or otherwise. The ink may be equalized on all parts of the rollers which pass over the form, by their rolling over a horizontal board which is turned slowly on a vertical axle by the motion of the press.

The various other ways in which the inventor has contemplated applying the foregoing principles are as follows: The mode of producing pressure before described is applicable to all descriptions of presses. Where it is necessary to continue the pressure a considerable distance the circumference of the rollers or rotating inclined planes, &c., should be increased accordingly. But where a mere incision is required such as for cutting the skinning or the skinning of the component parts must be proportioned to the distance which the die or part which produces the effect is required to move. These variations and likewise the particular applications which among the foregoing is best adapted to the required operation will readily suggest themselves to the skillful artist, who constructs the machine. In the preceding specification there may be found descriptions of parts of machinery common to the public or belonging to others which are introduced merely to illustrate the principles signifying with most propriety to the subscriber to the property stated and for which alone he claims an exclusive right.

"The Commissioner of Patents,
Washington, D. C."

DEPARTMENT OF THE INTERIOR,

United States Patent Office,

Washington, D. C., ... 189.....

SIR:

The printed *copy* of Patent No. *U. S. 600,000*
is *exhausted.*

As soon as printed a copy will be mailed you to complete your order.

By direction of the Commissioner:

Very respectfully,

Chief Clerk.
